HEEL BREAST COVERING CLAMPING
DEVICE

George Fredrick Lybrook, South Portsmouth, Ky.

Application September 30, 1938, Serial No. 232,627

4 Claims. (Cl. 12—125)

This invention relates to the manufacture of shoes and is particularly directed to a clamping device to facilitate the application of heel breast coverings to women's shoes.

5 The heel breast covering usually consists of a rearwardly extended portion of the sole, split and applied to the breast of the heel adhesively, as a continuation of the sole of the shoe. This practice is well known in the art and provides a neatly 10 finished bottom surface of uniform color and grain.

In the manufacture of shoes, the operation of applying the breast covering, known in the trade as "grain laying", usually follows the heel attaching operation. At this time, the breast of the heel and the untrimmed split sole extension or breast cover are given a coating of adhesive such as glue, and the cover is then laid upon the face 15 of the heel breast. Following this operation, a clamp may be applied over the covering to press it against the breast surface while the adhesive sets.

The improved clamping device of this invention is intended for use in holding the covering 20 in place against the heel breast, under pressure, while the adhesive coating sets. The device is preferably (but not necessarily) used in connection with wood heels, the covering being applied to the heel breast after the heel is attached to the shoe and while the shoe is still lasted. The improved clamp constitutes a unit in itself, requires no outside, pressure-applying element, and need not be attached to a fixed support. The pressure is applied directly to the heel breast, 25 tension being applied between the heel and the top of the last upon which the device is engaged. The clamp is quickly and readily applied and the shoe may then be placed in the rack for a period of time to allow the adhesive film to set, after 30 which the clamp may be removed. By utilizing the last of the shoe as an anchoring point for the clamp, distortion or marring of the shoe is avoided.

It has been an object of the present invention 35 to provide a small, light-weight, breast-covering clamp which is applied directly upon a lasted shoe without adding any appreciable bulk to the shoe. The construction of the device obviates the necessity for a stationary clamping fixture with a resultant saving in floor space and capital investment.

It has been another object to provide a clamp 40 of the type indicated, which may be readily applied or removed by hand, but which may be so securely positioned that the shoe can be moved

about and worked upon while the clamp is in place.

It has been another object to provide a heel clamp of the type indicated which applies a uniform pressure over the entire surface of the heel 45 breast and effectively prevents any wrinkling or buckling of the breast covering.

Other objects and further advantages will be more fully set forth in the specification, with reference to the accompanying drawing, in 50 which:

Figure 1 is a side elevation of a lasted shoe with the improved breast clamp in place thereon.

Figure 2 is a fragmentary perspective view of 55 the clamp removed from the shoe.

Figure 3 is a bottom plan view of the heel portion of the shoe showing the clamp applied thereon.

Figure 4 is a sectional view taken on line 4—4 of Figure 3.

Figure 5 is a sectional view taken on line 5—5 of Figure 1.

Figure 6 is a sectional view taken on line 6—6 of Figure 1.

Referring to Figure 1, the shoe is indicated 25 generally at 10, the last at 11, and the heel at 12. The clamping device, indicated generally at 13, is shown in place on the lasted shoe.

The clamping device is composed of a supporting yoke or stirrup 14, which straddles the heel. 30 A sheet of material or webbing 22, is affixed to the arms of the yoke and is held firmly positioned against the heel breast by an elastic loop or band 15, which encircles the heel portion of the shoe 35 and is engaged against the top edge or corner of the last. The elastic band forms a loop having the opposite lower ends secured to the yoke 14. The upper, or looped-over portion of the band engages the corner of the last, having for this purpose a line of stitching 16 conforming to 40 the shape of the corner. This line of stitching securely engages the last and holds the loop or band against displacement. The upper end of the loop is provided with a finger hold or tab 17, formed by inserting a short section of solid material, such as wood, indicated at 18 on Figure 6, 45 between the two lines of cross stitching, indicated at 19.

The band or loop 15 is formed of elastic material, preferably rubberized fabric. The clamp 50 is applied to the shoe by gripping the tab 17 between the fingers with the webbing 22 in place against the breast of the heel and drawing the band over the rear portion of the shoe as shown in Figure 1. The elasticity of the band provides 55

the necessary tension to hold the webbing firmly in contact with the heel.

The yoke 14 may be formed from a length of wire or rod, bent to a generally U-shaped configuration. The side arms are bent angularly adjacent to the light or cross member of the yoke as at 20, thereby positioning the cross member against the instep or arch of the shoe. The cross member may be covered with a resilient tubing 10 21, preferably of soft rubber, to protect the arch of the shoe against marring. The arms of the yoke carry a sheet of fabric, indicated at 22, which may be of yieldable or elastic fabric. The fabric may be attached to the yoke by inserting 15 the yoke arms in a hem formed along the opposite side edges of the sheet, as defined by the lines of stitching 23 (see Figure 2). The center portion of the elastic sheet may include a contact pad 25 stitched or otherwise secured thereto 20 and shaped to conform to the outline of the heel breast. The purpose of this pad is to fill in the center portion of the heel, particularly when the heel breast is concave in transverse cross section as shown in Figure 5. The contact pad 25 may 25 be formed of yieldable material such as rubber and should be adapted to conform to various types of heel breast cross sections whether square or concave.

As previously stated, the clamping device is 30 applied by hand, the loop 13 being grasped at the finger hold 17 with the webbing in place against the heel. The loop is then slipped over the rear portion of the shoe and engaged upon the last. The cross member 21 of the yoke 14 in 35 contact with the instep or arch portion of the shoe acts as a fulcrum point to rock the yoke rearwardly, thus disposing the fabric pressure sheet or webbing in firm contact with the breast covering. The upper portion of the breast in 40 the area where the heel breast and the arch are joined, is firmly pressed in place by the portion of the fabric sheet at the corner section 20 of the side elements. By this arrangement, the application of pressure to the heel breast is substantially uniform over the full length of the heel.

The usual course of manufacture is to apply 45 the breast covering to the heel before it is trimmed to the exact shape of the heel. After the clamping device is removed, the heel breast covering is trimmed to size by following the edges of the heel with a knife. In the use of the device of my invention the covering material is firmly pressed against the surface over the entire area of the heel breast. Since the pressure sheet 50 is stretched rearwardly along the corners of the

heel, as shown in Figure 5, the heel breast cover is securely affixed along the corners of the heel, thus insuring a neat job after the trimming operation previously described.

From the foregoing description it will be obvious that the cost of manufacture of the clamping devices is so small that a shoe manufacturer may utilize them in considerable quantities and thereby dispense with the use of large and expensive clamps of the permanent type which require 10 a substantial amount of floor space and represent a considerable capital investment. Likewise, the course of shoe manufacture is simplified, as shoes on which the clamps are positioned may be worked upon almost as readily as if the clamp 15 were not there.

Having fully described my invention, I claim:

1. In a device for clamping a heel breast covering in place, in combination, a yoke adapted to straddle the heel of a shoe, a sheet of elastic 20 webbing between the arms of the yoke, and means for holding said webbing positioned against the heel breast, said means comprising the cross bar of the yoke and an elastic loop secured to said yoke and adapted to fit over the heel portion of 25 the shoe.

2. A heel breast covering clamp comprising a yoke, a sheet of material carried by said yoke for engaging the heel breast, said sheet of material having a pressure applying pad secured 30 thereon and adapted to conform to the transverse cross section of a heel breast, and means for holding said pad positioned against a heel breast, said means including an elastic loop secured to the yoke and adapted to encircle the 35 heel portion of the shoe.

3. A device for clamping a heel breast covering to a heel breast upon a lasted shoe and comprising a yoke portion adapted to straddle the heel of a shoe having a sheet of webbing affixed 40 to the arms thereof, and means for holding said webbing positioned against the heel breast under pressure, said means including a loop secured to the yoke and adapted to fit over the upper heel portion of the last.

4. A device for clamping a heel breast covering to a heel breast upon a lasted shoe, said device comprising a yoke having bent arms, said arms being adapted to straddle the heel of the shoe, a sheet of material secured between said arms, 50 and a pressure applying member secured to said yoke and adapted to engage the upper portion of a last for holding said sheet of material firmly positioned against the heel breast.

GEORGE FREDRICK LYBROOK. 55
